TRAIN DESCRIPTOR SYSTEM

Frank Benedict, Rutherford, N. J., assignor to
General Railway Signal Company, Rochester,
N. Y.

Application February 17, 1932, Serial No. 593,565

28 Claims. (Cl. 246—124)

This invention relates to train describers, and more particularly to a train describer operated automatically, but subject to manual intervention if traffic varies from its normal schedule and such other intervention as may be found necessary.

In accordance with the present invention it is proposed to indicate at each platform or station of a plurality of successive stations along the trackway the kind of train or car that is approaching, such as local or express or the destination of such train or car, and to change these indications automatically as the various trains progress. Another feature to be accomplished by the present invention resides in the provision of manually controllable means at a starting station to give the proper indications at all platforms in the event that a different than the usual schedule of train movements is to take place. Another feature of the present invention resides in the provision of manually controllable means at each of the various stations or platforms, whereby if several trains are consolidated into one this manually controllable means may be actuated to cause the signals to properly indicate the elimination of one or more of the trains.

Other objects, purposes and characteristic features of the present invention will in part be obvious from the accompanying drawing and will in part be more particularly described herein-after.

In describing the invention in detail reference will be made to the accompanying drawing, in which:—

Fig. 1 shows one form of the present invention applied to a section of railway track diverging into two different tracks; and

Fig. 2 shows a modified form of apparatus for the starting station of the invention shown in Fig. 1 of the drawing.

Referring to Fig. 1 the track rails 10 have been shown divided into sections by insulating joints 11, each section of which includes the usual track battery 12 and a track relay T (with a corresponding exponent). Each of these track relays has a pole changer relay PC (with a suitable exponent) associated therewith. In addition to these relays there is also provided a stick relay S in the starting station O designated by a dotted rectangle, in which starting station there is also an alternate relay AR. This alternate relay AR causes the trains to be automatically designated as alternately being for one destination and then another destination, so that

manual intervention will not be necessary so long as the trains are started in this alternate fashion.

By referring to the drawing it is readily apparent that each pole changer relay by its polar contact controls the polarity of the next polar relay in advance, providing that the intervening track circuit is not occupied and has its track relay energized. Also, it is apparent that if a certain train moving in the normal direction of traffic, as indicated by the arrow, that is, from left to right, enters a track section when there is no other train in this track section, all these pole changer relays will be successively operated to a particular polar position, thereby causing the indicating lamps N or B (with proper exponents) located at the various station platforms, and the indicating lamps N or B (with suitable prefixes) located at the tower to be energized. An operator may be on duty in this tower to operate the switch machine SM, so that each train may take the proper track without delay, or the switch machine SM may be operated automatically in a manner as pointed out hereinafter. It is believed that the features of this system may be best understood by considering the operation of the system.

Operation.—Let us first assume that alternate Broadway and Nassau trains leave the starting station which is to the rear of the block containing track relay T⁰, and that the first train to reach station O is a Nassau train, it being noted that each of the platform lamps N⁰, N¹, N², N³ and N⁴ are all lighted, as shown in the drawing, to indicate that the next train is a Nassau train. The circuit for illuminating the lamp N⁰ may be traced as follows:—beginning at the terminal (+), contact 15⁰ of the relay PC⁰, wire 16⁰, lamp N⁰ to the other terminal (—); also the circuit for illuminating the indicating lamp ON may be traced as follows:—beginning at the terminal (+), contact 15⁰ of the relay PC⁰, wire 17⁰, lamp ON to the other terminal (—). The remaining Nassau lamps are illuminated through similar circuits having corresponding reference characters with distinctive exponents or prefixes.

The first train having left the starting station, as above described, eventually enters the block containing track relay T⁰, the consequent de-energization of the track relay T⁰ resulting in the opening of contacts 18 and 19⁰ and in the closing of contact 20 of the relay T⁰. Opening of the contact 19⁰ prevents changing of the polar positions of the relay PC⁰ until the train in question has left station O. Dropping of the contact 20

5

30

35

40

45

50

55

of the track relay T^0 reverses the polar position of the alternate relay AR causing its polar contact 21 to be operated to the left-hand position, so that the relay PC^0 will be reversed as soon as the track relay contact 19^0 closes, thereby indicating that the next train will be a Broadway train.

Let us now assume that the first train traverses the station O and enters the track section containing the track relay contact 19^1 , thereby isolating the relay PC^1 from the polar contact 22^0 of the relay PC^0 . As soon as the rear end of this first train clears out of the track section containing relay T^0 , the contacts 18 , 19^0 and 20 will again be raised, thereby energizing the circuit for the relay PC^0 with current of positive polarity, and thereby operating the contacts 15^0 and 22^0 to the right, which results in illuminating the indicating lamps B^0 and OB through the following circuits:—(1) beginning at the terminal (+), contact 15^0 of relay PC^0 to the right, wire 23^0 , lamp B^0 to the other terminal (-), and (2) starting at the terminal (+), contact 15^0 of relay PC^0 to the right, wire 24^0 , indicating lamp OB to the other terminal (-). The remaining lamps B , having other exponents and prefixes, are at times energized through similar circuits having like reference characters with distinctive exponents and prefixes.

Referring to the drawing it will be noted that the illumination of indicating lamps at the various platforms will be changed from N to B as this first train leaves a particular station, thus indicating that the next train will be a Broadway train. In a similar way the passage of each train will indicate the next train to approach.

So long as the trains are alternately Nassau and Broadway trains the system will function as intended. Let us, however, assume that both the second and the third trains are Broadway trains, it being understood that the second train will be properly indicated at station O when it reaches the same, but that the third train will be wrongly indicated. In order to correct this wrong indication the motorman of this second Broadway train will stop just before he reaches the station O and he will reach out and depress the push button PB mounted at a convenient place, as on a pole or on a subway wall. Depression of the push button PB closes a circuit readily traced in the drawing for the stick relay S, which relay S when picked up will be stuck up through the following stick circuit:—beginning at the terminal (+), front contact 18 of relay T^0 , wire 25 , stick contact 26 , wires 21 and 28 , winding of the relay S to the common return wire C connected to the mid-point of said split battery.

With the stick relay S thus stuck up and with the push button PB still depressed the pole changer relay PC^0 will be operated to its right-hand position (designating a Broadway train) through the following circuit:—beginning at the terminal (+), contact 30 of the push button PB, wires 31 and 32 , front contact 33 of the relay S, wire 34 , pole changer relay PC^0 to the mid-point of said split battery. This reversal of the pole changer relay PC^0 will cause each of the pole changer relays in advance thereof between it and the next train in advance to be operated to a corresponding right-hand position, to indicate at each of the intervening platforms that the third train is also a Broadway train. Picking up of relay S will also extinguish the lamp 9 by reason of opening of contact 8 of relay S, thereby in-

forming the motorman that he may release his push button. In a similar manner a motorman may change the indication from a Broadway indication to a Nassau indication by depressing the push button PN.

At the approach of each of the other stations or platforms 1 , 2 , 3 and 4 there are provided similar push buttons PB and PN (with proper exponents). These push buttons at stations 1 , 2 , 3 and 4 have also been provided to change the indicating character of the platform signals, not because there has been a change in the order of the trains, but possibly because one of the trains has been incapacitated and has been combined with the next train in the rear, so that it will be necessary to eliminate the indication for the second train. This elimination of the second train will take place automatically, for as soon as the second train couples itself to the first train they will both occupy the same track circuit and in so doing the second train indication will be entirely lost. If the combined train is to take the designation of the first train no change in the indication will be necessary and the push button PB or PN (with the proper exponent) need not be depressed. However, on the other hand, if the combined train is to take the designation of the second train, and assuming that to be different from that of the first train, the motorman will push the proper push button PB or PN to give the proper indication at the platforms up to the next train in advance.

It is obvious from the drawing that the indication at each of the various platforms is repeated at the tower, this being done so that the operator in the tower may be informed as to the order in which the trains are, and how they are progressing, and also that he may operate the switch machine SM through the medium of the lever SML to the proper position before the train has actually arrived, the switch machine being controlled through normal wire NW and reverse wire RW through suitable approach locking and interlocking contacts (not shown) included in the common wire of the switch machine SM. If, on the other hand, it is desired to dispense with the operator at the tower, the contact 22^4 of the polar relay PC^4 may be substituted for the lever SML by throwing the double-throw switch 37 toward the left, in which event the switch machine SM will be operated entirely automatically; the wires leading from the contact 22^4 have for convenience been designated NW ^{1} and RW ^{1} and are auxiliary normal and reverse wires, respectively, for controlling the switch machine SM automatically.

It will be noted that the pole changer relay PC^X does not have any indication lamps associated therewith. This relay PC^X is employed in cases where the distance between successive platforms or stations is so great that two trains are apt to get into the intervening section of track at the same time, and in order to avoid the second train having its signal indication lost for reasons explained hereinbefore, an intervening track relay and repeater pole changing relay, such as track relay T^X and pole changing relay PC^X are employed. For instance, if two trains having different destinations should occupy the section between platforms 2 and 4 at the same time, the indication of the second train will not be lost so long as these two trains do not occupy two adjacent track circuits at the same time, and in practice the motormen will be instructed to avoid

such simultaneous occupancy of adjacent track sections.

Modification Fig. 2

Instead of using separate push buttons PB and PN at station O for the purpose of manual intervention in the event that trains do not arrive to take alternate destinations, the lever L (see Fig. 2) may be substituted for the push buttons PB and PN and the stick relay S. In this modified form of the invention the lever L when in either extreme position through the medium of its contact 35 directly controls the alternate relay AR to the proper polar position, instead of cutting out the effect of this relay AR on the relay PC⁰ as by the back contact 33 of relay S in Fig. 1, and in controlling the relay PC⁰ directly by contact 21 of relay AR. It is readily apparent that if the lever L is maintained in its central position, the relays AR and PC⁰ will be alternately reversed as trains pass by and deenergize and reenergize the track relay T⁰ the same as in Fig. 1, and that such reversal does not take place when the lever L assumes one or the other extreme position, for this relay AR will be energized to a particular polar position depending upon the position of the lever L and this position of the relay AR will be repeated by the relay PC⁰ assuming the opposite position.

Having thus shown and described one rather specific embodiment of the present invention, together with a modified form of a starting station equipment for such system, and having rather specifically described how this system is to be used, it is desired to be understood that this should not be construed as a limitation of the scope of the invention, nor should it be construed as illustrating the exact construction preferably employed in practicing the invention, but that the specific system illustrated has been selected for the purpose of disclosing the principles of the invention and one way of practicing the invention, but that various changes and additions may be made to adapt the invention to the particular problems encountered in practicing the same, all without departing from the spirit thereof, except as demanded by the scope of the following claims.

What I claim as new is:—

1. In combination, a track layout comprising a plurality of routes each preselected for a different one of a plurality of trains, a plurality of passenger stations along the track, a pair of indicators at each station one of each pair being simultaneously displayed to distinctively indicate the particular route a particular one of said trains is to traverse, a polar relay for each station for controlling said indicators, a track circuit including a track relay at each station, and a circuit for each polar relay including a contact of the next polar relay in the rear and a front contact of the track relay of the adjacent track section.

2. In combination, a stretch of railway track diverging into two tracks through the medium of a track switch, a plurality of stations along the track, two train announcing indicators at each station one of each simultaneously indicating that an approaching train is destined to travel over one of said tracks and the other of each simultaneously indicating that an approaching train is destined to travel over the other of said tracks, a polar relay at each station for controlling the two indicators at such station, and means for controlling said polar relays in accordance with the progress of trains along the track.

3. In combination, a stretch of railway track diverging into two tracks through the medium of a track switch, a plurality of stations along the track, two train announcing indicators at each station one of which indicates the precursory arrival of a train for one destination and the other of which indicates the precursory arrival of a train for the other destination, a polar relay at each station for controlling the two indicators at such station, a switch machine for operating said track switch, means for controlling said switch machine to cause said track switch to assume a position to correspond to the polar position of the polar relay at the station at said track switch, and means for controlling said polar relays in accordance with the progress of trains along the track.

4. In combination, a stretch of railway track diverging into two tracks through the medium of a track switch, a plurality of stations along the track, two train announcing indicators at each station one of which indicates the precursory arrival of a train for one destination and the other of which indicates the precursory arrival of a train for the other destination, a polar relay at each station for controlling the two indicators at such station, a switch machine for operating said track switch, means for controlling said switch machine to cause said track switch to assume a position to correspond to the polar position of the polar relay at the station nearest said track switch, a track circuit for each section connecting two stations including a track relay, and means for controlling each polar relay including a contact of the track relay of the section in the rear of such polar relay.

5. In combination, a stretch of railway track diverging into two tracks through the medium of a track switch, a plurality of stations along the track, two train announcing indicators at each station one of which indicates the precursory arrival of a train for one destination and the other to indicate the precursory arrival of a train for the other destination, a polar relay at each station for controlling the two indicators at such station, a switch machine for operating said track switch, means for controlling said switch machine to cause said track switch to assume a position to correspond to the polar position of the polar relay at the station nearest said track switch, a track circuit for each section connecting two stations including a track relay, and means for controlling each polar relay in accordance with the position of the next polar relay in the rear providing the track relay associated with the section between such polar relays is energized.

6. In combination, a stretch of railway track diverging into two tracks through the medium of a track switch, a plurality of stations along the track, two train announcing indicators for each station one of which indicates the precursory arrival of a train for one destination and the other of which indicates the precursory arrival of a train for the other destination, a polar relay at each station for controlling the two indicators at such station, a switch machine for operating said track switch, means for controlling said switch machine to cause said track switch to assume a position to correspond to the polar position of the polar relay at the station nearest said track switch, a track circuit for each section connecting two stations including a track relay, a circuit for each polar relay including the contacts of the next polar relay

in the rear and a front contact of the track relay of the section between such polar relays, and manually operable means for changing the polar position of one of said polar relays.

5. 7. In combination, a stretch of railway track diverging into two tracks through the medium of a track switch, a plurality of stations along the track, two train announcing indicators for each station one of which indicates the precursive arrival of a train for one destination and the other of which indicates the precursive arrival of a train for the other destination, a polar relay at each station for controlling the two indicators at such station, a switch machine 10 for operating said track switch, means for controlling said switch machine to cause said track switch to assume a position to correspond to the polar position of the polar relay at the station nearest said track switch, a track circuit 15 for each section connecting two stations including a track relay, a circuit for each polar relay including the contacts of the next polar relay in the rear and a front contact of the track relay of the section between such polar relays, 20 and manually operable means for controlling said switch machine.

8. In combination, a stretch of railway track traversed by trains having different destinations at the exit thereof, a plurality of track relays 30 progressively controlled by the progressive advance of trains through said stretch of track, a plurality of stations along said stretch of track, a plurality of indicators at each of said stations, and means responsive to said progressive control of said track relays for progressively and selectively operating said indicators in accordance with the destination of said trains.

9. In combination, a stretch of railway track traversed by trains having different destinations 40 at the exit thereof, a plurality of track relays progressively controlled by the progressive advance of trains through said stretch of track, a plurality of stations along said stretch of track, a plurality of indicators at each of said stations, 45 means responsive to said progressive control of said track relays for progressively and selectively operating said indicators in accordance with the destination of said train and the next succeeding train, and manually controllable means for 50 changing the order of operation of said indicators by said trains.

10. In combination, a stretch of railway track traversed by trains having a plurality of destinations at the exit thereof, a plurality of track 55 relays progressively controlled by the progressive advance of trains through said stretch of track, a plurality of indicators at each of a plurality of locations, a plurality of control relays for controlling said indicators, means responsive to said progressive control of said track relays for 60 progressively and selectively operating said control relays, means controlled by said control relays for progressively operating said indicators in accordance with the advance of said train, 65 and means controlled by said control relays for selectively operating said indicators in accordance with the destination of said train.

11. In combination, a stretch of railway track traversed by trains having a plurality of destinations 70 at the exit thereof, a plurality of track relays progressively controlled by the progressive advance of trains through said stretch of track, a plurality of indicators at each of a plurality of locations, a plurality of control relays for controlling said indicators, means responsive to said

progressive control of said track relays for progressively and selectively operating said control relays, means controlled by said control relays for progressively operating said indicators in accordance with the advance of said trains, and means 5 controlled by said control relays for selectively operating said indicators in accordance with the destination of said trains.

12. In combination, a stretch of railway track traversed by trains having a plurality of destinations at the exit thereof, a plurality of track relays 10 progressively controlled by the progressive advance of trains through said stretch of track, a plurality of indicators at each of a plurality of locations, a plurality of polar control relays for 15 controlling said indicators, means responsive to said progressive control of said track relays for progressively and reversibly operating said control relays, means controlled by said control relays for progressively operating said indicators in 20 accordance with the advance of said train, means controlled by said control relays for alternately operating said indicators in accordance with the destination of said train and the next succeeding train, and manually controllable means for 25 reversibly operating said control relays to change the order of operation of said indicators by said train.

13. In combination, a track layout comprising a plurality of optional routes established through the medium of a track switch, a plurality of insulated track sections preceding said track switch 30 each section including a track relay, said track relays being responsive to the progressive advance of trains over said sections, and means responsive to the progressive operation of said track relays for automatically and alternately operating said track switch whereby said optional routes are 35 automatically and alternately established.

14. In combination, a track layout comprising 40 a plurality of optional routes established through the medium of a track switch, a plurality of insulated track sections preceding said track switch each section including a track relay, whereby 45 said track relays are responsive to the progressive advance of trains over said sections, and means responsive to the progressive operation of said track relays for automatically and selectively operating said track switch whereby said optional routes are 50 automatically and selectively established.

15. In combination, a track layout comprising a plurality of optional routes established through the medium of a track switch, a plurality of insulated track sections preceding said track switch 55 each section including a track relay, whereby said track relays are responsive to the progressive advance of trains over said sections, means responsive to the progressive operation of said track relays for automatically and selectively operating 60 said track switch whereby said optional routes are automatically and selectively established, and additional means for changing the order of operation of said track switch.

16. In combination, a track layout comprising a stretch of track having a plurality of optional routes at the exit thereof, a plurality of indicators for indicating the particular routes to be traversed by a plurality of trains, selecting means including a plurality of track relays progressively controlled in response to the progressive advance of trains over said stretch of track for alternately displaying said indicators to indicate that alternate trains will traverse alternate routes, and additional means operative to change the order 75

of display of said indicators to indicate that alternate trains will traverse the same route.

17. In combination, a track layout comprising a stretch of track having a plurality of optional routes at the exit thereof selected by a track switch, a plurality of indicators for indicating the particular routes to be traversed by a plurality of trains, selecting means including a plurality of track relays progressively controlled in response to the progressive advance of trains over said stretch of track for alternately displaying said indicators to indicate that alternate trains will traverse alternate routes, additional means operative to change the order of display of said indicators to indicate that alternate trains will traverse the same route, and means controlled by said selecting means for automatically operating said track switch in accordance with the routes to be traversed.

20 18. In combination, a track layout comprising a plurality of optional routes established through the medium of a track switch, an insulated track section preceding said track switch and including a track relay, means responsive to the successive advance of a plurality of trains over said section for controlling the repeated operation of said track relay, and means responsive to said track relay operation for automatically and selectively operating said track switch whereby each of said

30 trains is routed over said track switch in accordance with the route it is to traverse.

19. In combination, a track layout comprising a plurality of optional routes established through the medium of a track switch, an insulated track section preceding said track switch and including a track relay, means responsive to the successive advance of a plurality of trains over said section for controlling the successive operation of said track relay, means responsive to said track relay operation for automatically and selectively operating said track switch whereby each of said trains is routed over said track switch in accordance with its destination, and additional means for changing the order of operation of said

45 track switch.

20. In combination, a track layout comprising a stretch of track having a plurality of optional routes at the exit thereof selected by a track switch, a plurality of indicators for indicating the particular routes to be traversed by a plurality of trains, an insulated track section preceding said track switch and including a track relay, means responsive to the successive advance of a plurality of trains over said section for controlling the repeated operation of said track relay, means responsive to said track relay operation for selectively displaying said indicators to indicate the destinations of said trains, and means responsive to said track relay operation for automatically and selectively operating said track switch in accordance with the destinations of said

55 trains.

21. In combination; a track layout comprising a plurality of alternate routes; a plurality of passenger stations along the track; a pair of indicators at each station, one of each pair being simultaneously displayed to distinctively indicate the particular route over which an approaching train is destined to pass; a polar relay for each station for controlling said indicators; and means for controlling said polar relays in accordance with the progress of trains along the track.

22. In combination; a track layout comprising

5 passenger stations along the track; a pair of indicators at each station, one of each pair being simultaneously displayed to distinctively indicate the particular route over which an approaching train is destined to pass; a polar relay for each station for controlling said indicators; a track circuit including a track relay at each station; and means for controlling each polar relay in accordance with the position of the next polar relay in the rear only when the track relay associated with one of said polar relays is energized.

10 23. In combination; a track layout comprising a plurality of routes; a plurality of passenger stations along the track; a pair of indicators at each station, one of each pair being simultaneously energized to distinctively indicate the particular route over which approaching trains are destined to pass; a polar relay for each station for distinctively controlling said indicators; and means for controlling each of said polar relays in accordance with a preceding polar relay and also in accordance with the progress of trains along the track.

15 24. In combination; a track layout comprising a plurality of routes; a plurality of passenger stations along the track; a pair of indicators at each station, one of each pair being simultaneously energized to distinctively indicate the particular route over which approaching trains are destined to pass; a relay for each station for distinctively controlling said indicators; and means for controlling each of said relays in accordance with a preceding relay and also in accordance with the progress of trains along the track, and subject to track circuit control.

20 25. In a switching system for railways, a track section comprising a main track and a diverging route connected to said main track by a track switch, a power-operated switch machine for operating said track switch, storing means automatically controlled by the successive entrances of a plurality of trains into said main track for storing said entrances, and means including said storing means for successively operating said track switch.

25 26. In a switching system for railways, a track section comprising a main track and a diverging route connected to said main track by a track switch, a power operated switch machine for operating said track switch, storing means automatically controlled by the successive entrances of a plurality of trains into said main track for storing said entrances, and means including said storing means for successively controlling said switch machine as each train reaches said section.

30 27. A system for controlling the operation of a power-operated track switch to positions to conform with the destination of each train of a number of successive trains approaching the switch comprising; the combination with a power-operated track switch and controlling means for governing the operation of said switch to the normal or to the reverse position; a track circuit adjacent the switch; train destination 35 storing means including a plurality of electro-responsive units, each unit operable to assume different conditions to reflect the normal or reverse position of said track switch for a particular destination; manually operable means for controlling the conditions of the electro-responsive units of said storing means as each train approaches, one unit at a time and successively in a particular order and in a particular condition as said manually operable means is actu-

5

ated; whereby the actuation of said manually operable means in accordance with the destination of a number of succeeding trains which are to pass over said switch causes said storing means to register the destination of said number of succeeding trains in the order of their approach to said track switch; and means controlled by said track circuit for causing said storing means to successively operate said track switch in accordance with the different conditions assumed by the successive electro-responsive units thereof to cause the departure of one train to actuate or leave unactuated the track switch as required by the destination of the next 15 succeeding train, and to allow the electro-responsive unit which last operated said track switch to be again conditioned to reflect a destination for another train.

28. A system for routing a plurality of successive cars from a single track section capable of simultaneously containing a plurality of cars and extending from an entering point to an exit point into a plurality of route tracks through the medium of storing means for storing the plurality of car destinations in the same order as the cars pass the entering point for the purpose of setting up routes to these destinations as the successive cars pass the exit point comprising: the combination with power-operated means for establishing any one of a plurality of routes, each extending from the exit point into a par-

ticular route track; a track circuit adjacent said exit point; car destination storing means including a plurality of electro-responsive units, each unit operable to assume a condition to reflect the route over which the car which it characterizes is to move; a manually operable means for each route for controlling the condition of the electro-responsive units of said storing means as each car passes said entering point, one unit at a time and successively in a particular order and in a condition depending on the particular manually operable means actuated; whereby the actuation of a particular manually operable means defines a particular route for a particular car, of a number of succeeding cars which are to pass over said exit point, and causes said storing means to register a particular route for each of said cars in the order of their passage by the entrance point; and means controlled by said track circuit for causing said storing means to successively set up a particular route in accordance with the conditions defining destination assumed by the successive electro-responsive units thereof, to cause the departure of a car into a route to set up a new route as required by the route that the next car is to take, and to allow the electro-responsive unit which last set up a particular route to be again conditioned to reflect the route for another car passing the entrance point.

FRANK BENEDICT.
